H. L. BETTEN,
INTERLOCKING RAIL JOINT,
APPLICATION FILED MAR. 31, 1915.

1,163,126.

Patented Dec. 7, 1915.

UNITED STATES PATENT OFFICE.

HENRY L. BETTEN, OF ALAMEDA, CALIFORNIA.

INTERLOCKING RAIL-JOINT.

1,163,126.

Specification of Letters Patent.

Patented Dec. 7, 1915.

Application filed March 31, 1915. Serial No. 18,392.

To all whom it may concern:

Be it known that I, HENRY L. BETTEN, a citizen of the United States, residing at Alameda, in the county of Alameda and State 5 of California, have invented a new and useful Interlocking Rail-Joint, of which the following is a specification.

My invention relates to certain improvements in track structures and has relation 10 more particularly to a rail joint with the meeting ends of rails so overlapped and interlocking as to afford a practically continuous length of rail without the absolute necessity of binding such meeting ends of rails 15 together by the means of bolts or similar means of fastening.

The invention consists in the details of construction and in the combination and arrangement of the several parts of my improved 20 interlocking rail joint whereby certain important advantages are attained and the device is rendered simpler, less expensive and otherwise more convenient and advantageous for use, all as will be hereinafter 25 more fully set forth.

The novel features of the invention will be carefully defined in the appended claims.

In order that my invention may be the better understood, I will now proceed to describe 30 the same with reference to the accompanying drawings, wherein—

Figure 1 is a sectional view taken through a rail joint constructed in accordance with an embodiment of my invention; Fig. 2 is a 35 view in perspective of the meeting end of one of the rails compressed in my improved joint; and Fig. 3 is a view in perspective of the meeting end of the second rail comprised in my improved joint as herein set forth.

As disclosed in the accompanying drawings, 40 1 and 2 denote adjacent rails having their meeting ends provided with extensions 3 and 4, respectively, adapted, when assembled, to overlie in order to afford a scarf joint or connection and, as herein disclosed, the extension 3 of the rail 1 includes the head or tread of the rail and the lateral half of the web and one of the base flanges, as is believed to be clearly illustrated in the accompanying drawings; and it is to be observed 45 that in order that such extension, or more particularly the tread portion thereof, may have the requisite strength the adjacent web portion 5 of the rail is materially thick-

ened and it will also be observed that the 55 flanges 6 of the rails are also thickened. The inner face of the extensions 3 or more particularly the tread portion thereof, is provided in close proximity to the base thereof with the elongated shoulder or tongue 7 60 extending entirely therealong and of a thickness less than the thickness of the adjacent portion of the web 5, while the under surface of the head or tread portion 8 of the extension 3 is provided with the recess or 65 groove 9 substantially semicircular in cross section which is adapted to receive the rounded upper edge 10 of the extension 4 of the rail 2, such extension being herein shown as including the web portion 11 and the base 70 flanges 12, such web portion and the flanges being produced in a manner somewhat similar as has been set forth relative to the extension 3 except that in lieu of the shoulder or tongue 7, the inner or exposed face of the 75 extension 3 is provided with an elongated recess or channel adapted to snugly accommodate the shoulder or tongue 7, as is believed to be self evident. In assembling the rails, it will be readily perceived that the 80 rail, or more particularly the extension 3 thereof, occupies the inside position of the track structure and the interlocking or joining is effected by tipping the inner rail at an angle of about thirty degrees, hooking it 85 over the ends of the adjoining rails and then allowing the rail to drop into a vertical position whereby it will be seen that the grooves and shoulders or tongues on the rail 1 will promptly engage with the rounded edges 90 and the channel of the rail 2 and form a lock against separation by purely lateral or vertical strain and thereby avoid the use of bolts or the like.

From the foregoing description, it is 95 thought to be obvious that a track structure constructed in accordance with an embodiment of my invention is of an extremely simple and comparatively inexpensive nature and is particularly well adapted for use 100 by reason of the convenience and facility with which the meeting ends of the rails may be interlocked or joined and of the strength possessed by such joint and it will be obvious that my invention is susceptible 105 of some change and modification and for that reason I do not wish to be understood as limiting myself to the precise arrange-

ment and formation of the several parts herein shown in carrying out my invention in practice.

I claim:

1. A scarf joint for the meeting ends of rails comprising an extension on one of the rails including the head, web and a flange thereof, the extension of the web being of less thickness than the adjacent portion of 10 the web proper, the under surface of the head adjacent the inner side of the extension of the web being formed with a recess, and a tongue formed longitudinally of the extension of the web and projecting from the inner face thereof; the extension of the adjacent meeting rail end comprising the web and base, the upper edge of such extension being rounded and projecting within the recess in the extension of the head of the first 15 rail and said extension having a longitudinally disposed channel produced in its inner face adapted to receive the tongue on the inner face of the extension of the first rail, such rails being assembled by a relatively lateral tilting movement.
2. A scarf joint for the meeting ends of rails comprising an extension on one of the rails including the head, web, and a flange thereof, the under surface of the head adjacent the inner side of the extension of the web being formed with a recess, and a tongue formed longitudinally of the extension of the web and projecting from the inner face thereof; the extension of the adjacent meeting rail end comprising the web and base, the upper edge of such extension being rounded and projecting within the recess in the extension of the head of the first rail, such rails being assembled by a relatively lateral tilting movement.
- 30 3. A scarf joint for the meeting ends of rails comprising an extension on one of the rails including the head, web and a flange thereof, the under surface of the head being formed with a recess, the extension of the adjacent meeting rail end comprising the web and base, the upper edge of such extension projecting within the recess in the extension of the head of the first rail and said extension having a longitudinally disposed channel produced in its inner face adapted to receive the tongue on the inner face of the extension of the first rail, such rails being assembled by a relatively lateral tilting movement.
4. A scarf joint for the meeting ends of rails comprising an extension on one of the rails including the head, web and a flange thereof, the under surface of the head being formed with a recess; the extension of the adjacent meeting rail end comprising the web and base, the upper edge of said extension projecting within the recess in the extension of the head of the first rail; the web of one of the extensions of the rails being provided with a recess, the web of the second extension being provided with a tongue adapted to be received within said recess; said rails being assembled by a relatively lateral tilting movement.

face of the extension of the first rail, such rails being assembled by a relatively lateral tilting movement.

3. A scarf joint for the meeting ends of rails comprising an extension of one of the rails including the head, web and a flange thereof, the under surface of the head being formed with a recess, and a tongue formed longitudinally of the extension of the web and projecting from the inner face thereof; the extension of the adjacent meeting rail comprising the web and base, the upper edge of such extension projecting within the recess in the extension of the head of the first rail and said extension having a longitudinally disposed channel produced in its inner face adapted to receive the tongue on the inner face of the extension of the first rail, such rails being assembled by a relatively lateral tilting movement.

4. A scarf joint for the meeting ends of rails comprising an extension of one of the rails including the head, web and a flange thereof, the under surface of the head being formed with a recess; the extension of the adjacent meeting rail end comprising the web and base, the upper edge of said extension projecting within the recess in the extension of the head of the first rail; the web of one of the extensions of the rails being provided with a recess, the web of the second extension being provided with a tongue adapted to be received within said recess; said rails being assembled by a relatively lateral tilting movement.

In testimony whereof I hereunto affix my signature in the presence of two witnesses.

HENRY L. BETTEN.
